US0D1051359S

(12) **United States Design Patent** (10) **Patent No.:** **US D1,051,359 S**
(45) **Date of Patent:** **** Nov. 12, 2024**

(54) **AIRWAY DEVICE**

(71) Applicants: **INTERSURGICAL AG**, Vaduz (LI);
Muhammed Aslam Nasir, Caddington (GB)

(72) Inventors: **Andrew Neil Miller**, Crowthorne (GB);
Jane Elizabeth Kemp, Bristol (GB);
Muhammed Aslam Nasir, Caddington (GB)

(73) Assignees: **INTERSURGICAL AG** (LI);
Muhammed Aslam Nasir (GB)

(**) Term: **15 Years**

(21) Appl. No.: **29/726,982**

(22) Filed: **Mar. 6, 2020**

Related U.S. Application Data

(62) Division of application No. 29/676,952, filed on Jan. 16, 2019, now Pat. No. Des. 877,888, which is a division of application No. 29/548,655, filed on Dec. 15, 2015, now Pat. No. Des. 842,456.
